PAPER-MAKING METHOD

James A. Reitzel, Morris, Ill., assignor to Morris Paper Mills, Chicago, Ill., a corporation of Illinois

Application July 31, 1936, Serial No. 93,538

1 Claim. (Cl. 92—38)

The present invention relates to paper making and has particular reference to an improved process by which products such as paperboard may be produced in an effective and economical manner.

5 A principal object of the invention is the provision of a closed flow process for making paper.

An additional object is to provide a process for the manufacture of paper, in which the amount of water employed in the paper machine is controlled to provide a quantity of water suitable for return to the various steps of the process.

15 These and other objects will be observed upon a consideration of the following description of a preferred embodiment of the invention and by reference to the accompanying drawings, in which

20 Fig. 1 is a flow sheet and diagrammatic view of a paper-making process conducted in accordance with the present invention;

Fig. 2 is a side view of a preferred form of paper machine for carrying out the process of the invention; and

25 Fig. 3 is an end view of the device shown in Fig. 2.

In the production of paper it is customary to supply the materials from which the paper fibres are produced to a beater in which the material is disintegrated and the fibres are partially hydrated. Thereafter, the slurry of hydrated fibres is passed through a refining process and finally into a paper machine in which the slurry is deposited upon a perforated member which drains the water away and leaves a web. The web is picked up by a traveling felt and subjected to a finishing process, which includes drying the residual water from the web. Customarily, a number of web-forming devices are employed and the webs produced on the several devices are laminated together while in a wet condition. This is true in particular where a heavy paper product such as paperboard is produced. In many cases the composite product will include several filler layers and inner and/or outer liners. The present invention contemplates in particular the use of paper-making equipment of the drum type in which a drum partially is submerged in the slurry of fibre, the drum having as its cylindrical portion a fine mesh screen. A device of this type is indicated in Figs. 2 and 3. For clarity, only so much of the apparatus is shown as is necessary for understanding in the invention, it being understood that the equipment otherwise is conventional in construction.

To illustrate the improved process Fig. 1 represents a flow sheet in which there are two web-forming drums for producing a filler and an outer liner. Ordinarily, a larger number than this will be employed and the process will be extended to include these additional machines.

5 The fibrous materials from which the filler is to be produced are introduced into the beater 10 along with the requisite amount of water from the line 11. The beater is run until the proper disintegration and hydration are obtained, suitable chemicals such as alum and sizing being added in sufficient time to obtain a thorough mixture with the fibres. From the beater the slurry is introduced through line 12 in a stuff chest 13 which acts as a reservoir. In many cases this stuff chest will serve for several beaters, producing slurry from the same type of materials.

10 From the stuff chest the paper slurry is introduced through line 14 into a Jordan 15, this Jordan acting to further hydrate and refine the fibrous materials contained in the paper, the refined slurry from the Jordan passing through line 16 into a machine chest 17. Ordinarily, the paper slurry will contain about 3 per cent of fibrous material in the condition in which it reaches the machine chest. From the machine chest the refined paper slurry passes through line 18 into a paper machine head box 19. Ordinarily, some additional water will be added to the slurry in the head box from line 20, the fibrous content 15 of the slurry being reduced to the order of 2½ per cent. This slurry is heavier than is desirable for the paper-making machine and after passing through line 21 into a mixing box 22 the slurry is reduced in concentration to about 20 0.5 per cent, the diluted slurry passing through line 23 into a tank 24 in which the web-forming drum 25 partially is submerged. The ends of the drum 25 are closed to the slurry in the tank 24 and the drum rotates in the direction shown by the arrow. The slurry inside the tank 24 is at a higher level than the water inside drum 25 and this difference in head causes the water in the slurry to pass through the openings in the wire mesh which covers the drum, thereby depositing a continuous layer of fibrous materials on the drum. This continuous layer comes in contact with a traveling felt 26 and the latter carries the web forward.

25 The liner is formed in a manner similar to that described with respect to the filler. The materials from which the liner is produced are added to beater 27 along with the requisite amount of water, the latter being added to the

beater through line 28. From the beater 27 the hydrated and disintegrated slurry passes through line 29 to a stuff chest 30. The stuff chest 30 delivers the slurry through line 31 to a Jordan 32 where the paper fibre is further hydrated and refined. From the Jordan the refined paper stock passes through line 33 to a machine chest 34 and from this machine chest the slurry passes through line 35 to a paper machine head box 36. The consistency of the stock in the head box may be reduced by water introduced through line 37. A line 38 carries the paper stock from the machine head box to a mixing box 39. The consistency of the stock in the mixing box is further reduced by the mixing of water through line 40.

From the mixing box 39 the diluted paper stock passes through line 41 to a tank 42, in which is partially submerged a web-forming drum 43. This drum rotates in the same direction as the drum 25, as shown by the arrow, and picks up a continuous web of paper which is deposited on the filler web carried by the felt 26. It will be understood that the combined web subsequently is handled in the usual manner for producing a finished paper, including the steps of taking the web off the felt and passing it through a drying process.

The fibres from which the paper is produced are hydraulically deposited on the drums 25 and 43 in interlocked relation and when the web is picked up by the felt some of the fibres remain attached to the drum. If these attached fibres are allowed to accumulate the screens on the drums are at least partially stopped up and the proper formation of the web is interfered with. For this reason the drums are provided with suitable cleaning devices. In Fig. 1 the cleaning device for drum 25 is indicated at 44 and consists of a reciprocating nozzle, the construction of which is shown more particularly in Figs. 2 and 3, the nozzle being supplied with shower water through line 45.

The drum 43 is provided with a similar shower nozzle 46 having a water supply line 47. The construction of the shower mechanism is of particular importance and will be described more fully with reference to Figs. 2 and 3 hereafter.

The felt 26 likewise picks up fibres during the period of its contact with the newly formed paper web and the accumulation of such fibres is objectionable. For this reason the felt is passed adjacent a shower 48 on its return travel. This shower generally consists of a stationary perforated pipe to which fresh water is supplied through a line 49. The water from the felt shower falls into a receiving trough 50 and is transferred therefrom to a sewer or other suitable source of disposal through line 51. This water is relatively clean, since the amount of impurities picked up from the felt is small, and disposal of the water offers substantially no problem from the standpoint of sanitation or stream pollution.

The water which passes through the drum 25 in the process of depositing the paper fibres and the wash water from the shower 44 collects in the drum and is withdrawn therefrom through line 52. After passing through an open box 53 this water is transferred through line 54 to a conventional saveall 55. From the saveall the water passes through a catch box 57. The catch box is provided with a conventional volume control arrangement such as a float-controlled valve and the quantity of water in the process is maintained constant by conducting a stream through line 58 from the discharge line 51 of the felt-

washing system. It will be understood that the paper web formed on the drum 25 carries a substantial quantity of water out of the process and to replace this, water is taken through line 58 from the felt shower. The catch box 57 is provided with a suitable mechanism such as a float-operated valve for maintaining the quantity of water constant. Thus, the valve determines the amount of water taken through line 58. From the catch box 57 the process water coming from the drum 25 and the make-up water received from line 58 is pumped through line 59 which terminates in connection with a storage tank 60 designed to supply the beater 10 through line 11. Lines 20 and 45 leading respectively to the head box 19 and the drum shower 44 are connected with line 59. Additionally, a line 61 leads from line 59 to the mixing box 22 for supplying additional quantities of water of dilution. Any water which is not taken through lines 20, 45 and 61 passes through a heater 62 which maintains the temperature of the water sufficiently high to facilitate the paper-making process. As the principal quantity of this water has been recirculated the amount of heat required for maintaining the process water at the proper temperature is substantially less than where fresh water is employed in the beaters.

The water which accumulates in the drum 43 is taken through line 63 to a tank 64 which serves the beater 27. Line 63 supplies the water of dilution passing through lines 37 and 40 and the wash water for the shower 46 which passes through line 47. Adjacent the tank 64 the line 63 passes through a suitable heater 65 which is similar in function to the heater 62 and maintains the water at an elevated temperature. Make-up water passes from the sewer line 51 to line 63, thereby replacing the water passing out of the process with the paper web.

The water employed in the felt shower preferably is clean water and as the felt is relatively clean the water passing through line 51 contains very little suspended matter. In employing this felt shower water as make-up water the concentration of impurities in the process is reduced and at the same time additional quantities of fibrous materials are saved.

The construction of the drum-washing devices 44 and 46 is shown in Figs. 2 and 3 and as the construction of these devices is the same, the same reference numerals will be employed in connection with the description thereof. The tanks 24 and 42 in which the drums 25 and 43 respectively are partly submerged are separated by a dam 66. To the lines 45 and 47 which supply the water needed in the shower are connected flexible rubber tubes 67. Tubes 67 lead to upper connections 68, the latter being joined to an inner pipe 69 which is slidably carried in a stationary outer guide pipe 70 extending transversely of the drums. The inner pipe 69 carries two nozzles 71 and 72 spaced apart a distance equal to half the length of the drums.

The outer guide pipe 70 is slotted to allow reciprocation of the nozzles 71 and 72 and also extends outwardly beyond the machine at one end as shown in Fig. 3. This end extension is slotted to allow reciprocation of the connection 68. A drive connection 73 is secured to the end of the inner pipe 69 and passes upwardly through a longitudinally extending slot in the outer pipe 70. To this drive connection is secured an upwardly extending arm 74, the latter being telescopically received in a sleeve arm 75, which is pivotally

mounted in the frame structure 76, as shown at 77. The upper end of arm 75 is slotted, as shown at 78 and carries a slidably arranged drive rod 79, the latter being secured at 80 to a rotating disk 81. Disk 81 is driven by means of motor 82 through belt 83 and suitable reducing gearing at a slow speed. It will be seen that as the disk 81 rotates the arm 75 is reciprocated, thereby moving the inner pipe 69 and the nozzles 71 and 72 transversely of the paper-making drums. The nozzle 72 serves one-half the drum while nozzle 71 serves the other half. Water in pressure passes out of the nozzles and sprays directly against the perforated drums. The nozzles are traveling during the washing period and this seems materially to assist in the effectiveness of the washing action. It is preferred to direct the nozzles at a downward angle with respect to the drums, which is more perpendicular than a radial line drawn through 20 the nozzles.

The cylinder-washing device described is so effective in cleaning the cylinders that the time formerly required for shutting down the machine and cleaning the cylinders with solvents and the 25 like is saved. By employing a restricted spray nozzle in the manner described, the total amount of wash water employed in the process is greatly reduced over former practices. The washing operation is more effective by use of the device described and the process water moves through the system sufficiently fast to keep down bacterial action and reduce the tendency toward sliming which has been experienced heretofore. By reducing the amount of water employed in washing 30 the drums and in returning the process water to the beaters, a substantial savings in the chemicals employed for sizing and other purposes is made. The quantities of the chemicals added to the beater which are not absorbed by the paper fibre 40 are returned to the beater so that in providing for a new batch of material it is necessary only to add further quantities of chemicals to the extent sufficient to replace the absorbed quantities. In many cases the saving effected in the chemicals 45 will be of the order of 50 per cent.

In a preferred embodiment of the process, water from line 51 is carried to the supply line 49 for the felt showers. The supply of fresh water employed for washing the felt thereby may be limited to the volume of water withdrawn as make-up water for the paper process. In such a process there are two circulatory systems in which the felt-washing cycle introduces fresh water which partially is circulated and partially passed 50 into the paper-making cycle. Fresh water is 55

brought into the process at the felt shower and process water is withdrawn from the system incorporated in the paper web. Each cylinder is provided with its own circulatory system. That is, the process water from the filler drum is returned to the filler beater without admixture with the water of the liner system. 5

The shower nozzles for the paper machine cylinders are arranged so that each nozzle reaches a position adjacent the outside of the drum at one 10 stage of the reciprocation. The reciprocal movement may be stopped at such positions, so that access may be had to the nozzles for cleaning. In traveling across the drum while the latter is rotating, the water from the nozzles washes the 15 drum along narrow spiral bands which may be of a width of the order of 1 or 2 inches, the relative motion of the cylinders and nozzles being such that different parts of the cylinders are served by the nozzles at each cycle of reciprocal 20 movement. The relatively small openings in the nozzles greatly reduce the amount of water employed in washing the cylinders and allow for the use of a higher water pressure without requiring undue power consumption. A pressure of around 25 40 pounds and a volume of around 5 gallons per minute for each of the two nozzles of the cylinder showers has been found satisfactory.

Use of the cylinder-washing mechanism cuts down the amount of water entering the process 30 and raises the concentration of the process water which is circulated in the manner described.

The process and apparatus may be changed in many respects from the forms described herein for purposes of explanation without departing 35 from the scope of the invention as defined in the appended claim.

I claim:

In a paper-making process, the steps which include passing a slurry of fibre through a 40 foraminous surface to form a web and slurry water, passing a felt adjacent said surface to take off said web, washing adhering fibres from said felt with fresh water, washing adhering fibres from said foraminous surface with a re- 45 stricted stream from a reciprocating spray, combining said slurry water and said foraminous surface wash water with a portion only of the felt wash water, adding a portion of said combined water to paper stock to form additional 50 slurry, and returning a remaining portion of said combined wash and slurry water to the restricted stream from the reciprocating spray.

JAMES A. REITZEL.
